UNITED STATES PATENT OFFICE.

WILLIAM MCFADYEN, OF GLASGOW, COUNTY OF LANARK, SCOTLAND,
ASSIGNOR TO ARNOLD, CONSTABLE & CO., OF NEW YORK, N. Y.

DESIGN FOR A RUG.

SPECIFICATION forming part of Design No. 19,583, dated January 14, 1890.

Application filed December 18, 1889. Serial No. 334,197. Term of patent 3½ years.

To all whom it may concern:

Be it known that I, WILLIAM MCFADYEN, a subject of the Queen of Great Britain, residing at Glasgow, in the county of Lanark, 5 Scotland, have invented and produced a new and original Design for a Rug; and I do hereby declare that the photographic print accompanying this specification conveys to any one skilled in the art a clear understanding of the 10 same, and is sufficient to enable such persons to use my invention.

What I claim as my invention, and desire to secure by Letters Patent, is—

The design for a rug, consisting of the ornamentalations shown in the photographic print 15 accompanying this specification.

WILLIAM MCFADYEN.
